C. L. HERSHY

TIME ACTUATED ELECTRIC SWITCH

Filed Dec. 10, 1925

Patented Aug. 14, 1928.

1,681,116

UNITED STATES PATENT OFFICE.

CLARENCE L. HERSHY, OF LEAMAN PLACE, PENNSYLVANIA.

TIME-ACTUATED ELECTRIC SWITCH.

Application filed December 10, 1925. Serial No. 74,529.

This invention relates to electric switches and has more particular reference to a time control means for actuating the switch for closing an electric circuit to electric lighting 5 means.

The primary object of my device is to provide a switch of this character that may be installed as a unit, preferably within a hen house, in order that the electric lights 10 may be turned on prior to the day's sunrise so that artificial light will be provided for rousing the hens in order that they will begin laying thus producing a supply of eggs prior to sunrise.

15 A further and important object is to provide a time controlling switch mechanism that may be associated with the well known type of electric switch, which will be so associated with the time controlled mechanism 20 as to provide a complete unit within itself, that may as above stated, be readily set up in a hen house or the like.

25 A still further object is to substantially improve and simplify over previously patented and used devices of this character.

With the foregoing and other objects in view as the nature of the invention will be better understood, the same comprises the 30 novel form, combination and arrangement 20 of parts hereinafter more fully described, shown in the accompanying drawing and claimed.

In the drawing wherein like reference characters indicate corresponding parts 35 throughout the several views:

Figure 1 is an exterior elevation of the unit.

Figure 2 is a similar view disclosing the internal mechanism thereof, and

40 Figure 3 is a detail section disclosing the preferred manner of association of one member of the switch control mechanism with the alarm winding shaft of a conventional form of alarm clock.

45 Now having particular reference to the drawing, my novel mechanism constitutes the provision of a box-like casing 5, disposed upon a base board 6 that may be readily secured to the floor or wall of a hen house, or other building wherein the same is 50 disposed.

55 Located within the casing 5 is a well known type of electric snap switch 7 to the positive and negative contacts of which are electrically connected ends of cables 8 that are in electric circuit with one or more elec-

tric lights as well as a source of electric power, said cables extending through suitable openings in the casing, as is shown in Figure 2.

The front wall of the casing 5 is formed with an opening within which is rigidly disposed a conventional form of alarm clock 9, the outer face of which is exteriorly of the casing, while the inner face thereof is within 60 the casing as clearly shown in Figures 1 and 2.

In carrying out my invention I remove the usual winding means from the clock alarm winding shaft A, which is screw 70 threaded as shown in Figure 3. I then thread upon this shaft an internally threaded sleeve 10 that is formed upon the inner end of a rod 11 at right angles thereto. Said rod extends outwardly in spaced parallel relation with the clock and is pivoted at its outer end as at 12 to the lower end of a connecting rod 13, which rod extends upwardly and it is in turn pivoted at its opposite end as at 14 to an arm 15, in general parallel relation with the rod 7. The inner end of this arm is so constructed as to provide a clamping means whereby the same may be rigidly connected to the usual thumb button B, of the switch 7. 75

Connected to the rod 11 intermediate the ends thereof is one end of a retractile coil spring 16, the other end of which is secured through the medium of a hook to the wall 80 of the casing upon which is disposed said 90 switch 7.

In the position of the structural element as shown in Figure 2, the switch 7 is in "off" position. Obviously, after the alarm mechanism has been set to go off at a pre-determined time, the winding shaft A will 95 be released when this time is reached, and through the medium of the spring 16 the rod 11 will be thrown upwardly in the direction of the arrows, Figure 2, for then moving 100 upwardly upon the rod 13 and consequently the arm 15 which will move the button of the switch to closed position, and consequently permit the current to flow to the lighting means. 105

When it is desired to switch off the lights and rest the device, it is only necessary that the rod 13 be grasped and then forced downwardly for again moving the elements to the position shown in Figure 2 where they will 110 be so maintained until the set time has again been reached.

It will thus be seen that I have provided a highly novel, simple, and efficient form of time control electric switch mechanism that may be readily set up in hen houses or the like as a unit, and wherein the construction of the same is of such a simple nature as to not readily become out of order, and that may be manufactured and marketed at low cost.

10. Minor changes may be made in the invention without departing from the spirit and scope of the appended claim.

Having thus described my invention, what I claim as new and desire to secure by Letters Patent is:—

In combination, a casing, an electric snap switch located within the casing, an alarm clock arranged within the casing, a rod, an internally threaded sleeve formed on the 20 inner end thereof and disposed at right angles thereto, said sleeve being adapted for

engagement on the threaded end of the alarm winding shaft of the clock, an arm, a two-part clamp for securing the inner end of said arm to the button of the snap switch end of the arm forming one section of the two part clamp, a connecting rod secured at one end to the outer end of the first mentioned rod, the other end being secured to the outer end of said arm so that said arm will be moved to a switch actuated position when the first mentioned rod is operated by reason of the alarm winding shaft being released, and a retractile coil spring being secured at one end to the intermediate portion of the first mentioned rod, and at its opposite end to the casing, for immediately so moving the arm to a switch closing position when the alarm winding shaft is released.

In testimony whereof I affix my signature.

CLARENCE L. HERSHY.
